1 Sheet Drawing. 8 Pages Specification

A slide adapter for interchangeably receiving relatively small transparency mounts and adapting them for use in a slide projector designed to accommodate larger transparency mounts. This adapter comprises a windowed frame member having overall dimensions comparable to the larger transparency mounts and having a recess in one face thereof into which the smaller transparency mount can be inserted flatwise. The smaller transparency mount is held in this recess by a plurality of flexible fingers the free ends of which overhang the outer face of the relatively small transparency mount when it is properly seated in the recess of the adapter.
